UNITED STATES PATENT OFFICE.

JOHN L. DAWES, OF PITTSBURGH, PENNSYLVANIA.

SAND-BLAST MACHINE.

1,173,178.

Specification of Letters Patent. Patented Feb. 29, 1916.

Application filed June 16, 1915. Serial No. 34,463.

To all whom it may concern:

Be it known that I, JOHN L. DAWES, residing at Pittsburgh, in the county of Allegheny and State of Pennsylvania, a citizen 5 of the United States, have invented or discovered certain new and useful Improvements in Sand-Blast Machines, of which improvement the following is a specification.

My invention relates to sand blast 10 machines, and the object thereof is to provide a machine suitable for sand blasting various shaped articles, but which is particularly adapted to sand blast the substantially plane faces of disk-shaped lamp globes.

15 A further object of my invention is to provide a machine so constructed that the bearings of operating or movable parts will not be cut or worn by the sand.

In the accompanying sheets of drawings, 20 which form part of my specification, I have illustrated the preferred embodiment of my invention.

Figure 1 is a side elevation of the machine; Fig. 2 a sectional view taken on 25 the line II—II, Fig. 1; Fig. 3 a detail sectional view taken on the line III—III, Fig. 2; Fig. 4 a further detail sectional view taken on the line IV—IV, Fig. 2; but showing a plate in sand blasting position rather 30 than the globe of Figs. 1 and 2; Fig. 5 a view similar to the upper portion of Fig. 2, but showing a spherical lamp globe mounted on different turning mechanism than that of Fig. 2; Fig. 6 a sectional view to enlarged scale of the blast nozzle; and Fig. 7 a sectional view to enlarged scale of the sand receiver.

In the several figures like numerals are 40 used to designate like parts.

In the practice of my invention the sand blasting takes place within a casing adapted to retain the sand and dust, and means are provided within the casing for supporting and moving various forms of articles to be 45 sand blasted. Furthermore, means, operated by mechanism outside of the casing, are provided for reciprocating the blast nozzle within the casing.

The casing may be of any suitable shape, 50 but, as shown herein, is preferably rectangular, comprising side walls 1 and 2, end walls 3 and 4, and top 5. The lower portion of the casing is provided with a partition 6, which, with the casing walls, forms 55 a sand bin 7. The sand blast nozzle may be of any suitable construction, that shown

particularly in Fig. 6 comprising a T-fitting 8, to one leg of which there is attached a discharge tip 9, to another leg a flexible hose 10, leading to the sand bin 7, and to the third leg a pipe 11, which, through a second T-fitting 12, is attached to a flexible air supply hose 13. To the end that the flow of sand through the hose 10 will be even and continuous, a sand receiver 14, 60 provided with perforations 15, is attached to the lower end of such hose and embedded in the sand within the bin 7. The sand strained through the perforations 15 will, by the suction of the air escaping from the pipe 11, be drawn upwardly through the 65 hose 10 and projected against an object to be sand blasted.

Mechanism is provided for reciprocating the nozzle, and is constructed and arranged 70 in such a manner that there will be no relatively-movable machine-bearing parts exposed to the floating sand particles within the casing. For this purpose the side wall 1 is provided with a vertically disposed slot 80 16, through which there extends a rod 17, attached at its inner end to the T-fitting 12, and at its outer end slidably mounted on a suitable guide 18. The rod 17 is reciprocated vertically by means of a pitman 85 19, adjustably connected to a crank arm 20, secured to a shaft 21, which shaft may be driven in any suitable manner, as by a belt 22.

To prevent dust and particles of sand 90 from escaping through the slot 16 an elongate plate 23 is attached to the rod 17 and reciprocates therewith, such plate being held in vertical position by means of supports 24 to which the guide 18 is attached.

While, as will be presently explained, my 95 machine may be employed for sand blasting various shaped articles, it is particularly adapted to sand blast the substantially plane faces of disk-shaped lamp globes, such a globe being shown in Figs. 2 and 3. Heretofore considerable difficulty has been experienced in effecting an even sand blasting treatment of such globe faces. In the 100 mechanism which I provide for this purpose, the plane face of the globe to be sand blasted is held perpendicular to the line of blast, and the globe is rotated upon an axis passing through substantially the center of, and perpendicular to, such face. As seen in Figs. 2 and 3, a shaft 25 is mounted 105 in the side wall 2, and is adapted to be 110

rotated by a belt 26 extending from the shaft 21. The inner end of the shaft 25 is provided with a transverse bar 27 to which arms 28 are adjustably connected, such arms 5 being provided with adjustable globe-engaging members 29.

It will be observed that, by such an arrangement, the vertical movement of the nozzle will be harmonic, or stated differently, will be more rapid when in line with the center of the globe face than when in line with the outer edge thereof, the rate of movement of the nozzle varying gradually as it moves to and from the center of 15 such face. Thus there will be a substantially even sand blasting treatment of the entire area of the circular globe face.

In the machine shown herein means are also provided for carrying a plate or like 20 article transversely to the line of sand blast. For this purpose I preferably provide a conveyer belt 30, driven by a belt wheel 31, keyed to a shaft 32, which shaft in turn may be driven by a belt 33. The shaft 32 is 25 supported on a bracket 34 attached to the casing wall 3, and a second bracket 35, attached to the wall 4, supports an idler 36 for the conveyer belt. As will be seen, the walls 3 and 4 are provided with doors 37 30 and 38, respectively, so that plates may be placed upon and removed from the belt 30, as well as for general access to the casing. For supporting the upper ends of plates I provide a pivoted rack 39, which, as shown 35 in Fig. 4, may be swung downwardly to hold a plate 41 from falling rearwardly, or when not needed, may, as shown in Figs. 2 and 5, be retained in an upward position by catches 40. It will be understood of 40 this feature of my machine that the conveyer may be moved at the proper speed to permit a plate carried thereon to be sand blasted by the reciprocating nozzle.

Means are also provided for holding and rotating a substantially cylindrical lamp 45 globe in front of the sand blast nozzle. This is shown particularly in Fig. 5, wherein a globe 42 is suitably attached to the end of a shaft 43 rotatably mounted in the casing top 5, and, through bevel pinions 44 50 and 45, driven by the power shaft 21.

To the end that the dust and floating particles of sand may be removed from the casing, a suction dust conveyer 46 is attached to the top of the casing. 55

I claim as my invention:

1. In a sand blast machine, the combination of a closed casing, a sand blast nozzle within said casing mounted for rectilinear reciprocation, a rotatable member, a pitman 60 connected to said nozzle and eccentrically to said member, a blank holder rotatable upon an axis substantially coincident with the axis of said nozzle when in its intermediate position and coördinated means for 65 rotating said member and blank holder.

2. In a sand blast machine, the combination of a closed casing, a sand blast nozzle within the casing, mounted for rectilinear reciprocation, a rotatable member, a pitman 70 connected to said nozzle and eccentrically to said member, a blank holder comprising a rotatable shaft having its axis substantially coincident with that of the nozzle at its intermediate position, rods extending 75 transversely of and attached to said shaft, arms secured to said rods and adjustable radially with relation to said shaft, and adjustable blank-engaging members secured to such arms. 80

In testimony whereof I have hereunto set my hand.

JOHN L. DAWES.
